UNITED STATES PATENT OFFICE.

ROWLAND T. WALES, OF NEW ROCHELLE, NEW YORK.

MOLD FOR CONCRETE.

Application filed June 6, 1921, Serial No. 475,340. Renewed February 28, 1924.

To all whom it may concern:

Be it known that I, ROWLAND T. WALES, a citizen of the United States of America, residing in New Rochelle, in the county of 5 Westchester and State of New York, have invented certain new and useful Improvements in Molds for Concrete, of which the following is a specification.

This invention provides certain improvements in molds for use in building structures of concrete or similar material, or for facing or covering structures with such material. The particular construction of molds to which these improvements apply 10 embodies the following. The facing plates comprise panels of wood or of sheet metal against which the concrete or similar material is molded. They may be simple boards or channels of sheet metal. The facing plates are called plates herein. They are supported by a framework comprising a series of supports disposed adjacent the mold space and preferably having flanges extending laterally from them and 15 also adjacent the mold space. The plates are held in position by means of locks which engage the supports. The supports may be disposed vertically, horizontally or inclined, to correspond with the face of the mold desired. Likewise they may be either 20 straight or curved, a curved support being adapted for the inside of sewer or subway construction. The relative positions of plates, locks and supports will be substantially the same for different kinds of work. 25 In wall forms the supports are also known as studs. In ceiling forms they are also known as joists. The supports are preferably formed with wood or equivalent 30 facings to which may be nailed any accessories desired thereon, such as strips for ornamentation, cores for openings, sticks to hold bulkhead panels, and panels or studs at the corner of a wall. Holes for tie 35 rods may also be bored through the wood facings of the supports at any desired points and at any desired angles. The supports 40 may be secured and held in position by any usual or suitable method for securing and holding such members. An advantageous 45 means is shown herein which comprises an improved kind of stringer. The plates are adjustable and movable relatively to the supports and adjustable into and out of position 50 without affecting them. Plates are likewise adjustable and movable without affect-

ing adjacent plates except in special cases. Each lock may be adjustable relative both to plates and supports, without moving the supports, other locks or other plates than the 60 plate or plates immediately held by it. Such construction permits using the same plates and locks repeatedly in different parts of the same framework of supports before a job is completed. It also permits taking down the 65 supports after stripping of plates and using the same supports again in another part of the job. While two supports are in any one upright position, a plate can be used between them repeatedly at subsequently higher 70 levels, each removal of the plate being made after the concrete behind it has become hard enough to stand up in the small area which the plate covered. The construction of molds described in the foregoing has 75 the following advantages over other kinds of molds.

1. Uses less mold material on a single job.
2. Uses the same mold material repeatedly and without destruction on successive jobs. 80
3. Is erected and dismantled quicker and with less labor.
4. Permits easy placing and supporting of any iron reinforcement within the mold space before the plates are locked in position. 85
5. Possesses all advantages of panel molds without sacrificing the strength and accuracy possible by using studs or joists as in other kinds of molds. 90

This invention provides certain new and useful improvements pertaining to the construction described in the foregoing and has made it more practical. Some of the objects accomplished by these improvements 95 are given in the following:

1. Improved method of engaging the supports by the locks whereby the inserted end of each lock is seated in a hole in the opposite side of the support from where the lock is inserted, and thus the inserted end is rendered free from possible obstruction by any accidental deposit or layer of cement. By further having the inserted end of the locks seat in depression, no protruding obstructions result, and the assembling 100 of the panels or plates and other parts adjacent the lateral sides of the supports is rendered more facile.
2. Improved metal ties arranged with 110 in the lateral sides of the support whereby the thickness of the flanges on the support

and adjacent the mold space are not increased.

3. Improved construction of supports, resulting from the interior arrangement of the metal ties which may be brazed or arc-welded to the support, whereby all unnecessary increase in the thickness of the flanges or other projections on the lateral faces of the supports is eliminated. (Previous constructions have required either exterior welds or rivet heads.)

4. Improved means for holding the wooden or equivalent facings on the supports.

5. Improved means for assembling the stringers on the supports.

6. Improved bolt cleats for preventing rotation of the bolts. These may remain permanently assembled with the stringers and support-splices and do not require separate holes in the supports. Each is inserted in the support simultaneously with the bolt and automatically locks the bolt against rotation.

The invention also includes certain other features of improvement which will be hereinafter more fully set forth.

Referring to the drawings which are illustrative of the invention,—

Figure 1 is a top plan view of a portion of the mold showing a pair of supports and a pair of stringers spliced together.

Fig. 2 is a longitudinal section of the support showing one lateral side, the wood or equivalent facing and the metal ties for holding the facing in position.

Fig. 3 is an elevation of the support, viewing it from the outer side of the mold.

Fig. 4 is a horizontal section of the support showing the improved plate lock in position.

Fig. 5 is an elevation of the support splice with the bolts and cleats removed as viewed when looking in the direction of arrow 5 in Fig. 6.

Fig. 6 shows an end elevation of the support splice shown in Fig. 5.

Fig. 7 is an elevation of the improved stringer splice.

Fig. 8 shows an end elevation of the splice shown in Fig. 7.

Fig. 9 is a view partly in side elevation and partly in section showing the manner of splicing together two support sections, and also a special convenient manner of attaching a stringer to the support near the corner of a wall.

Fig. 10 is a view partly in side elevation and partly in section showing a stringer attached to a support in the preferred standard manner.

Fig. 11 is an elevation of my improved bolt cleat, and

Fig. 12 is a cross section thereof, taken on the line 12—12.

65 Referring to the drawings, let A indicate

a portion of a concrete or other construction formed or molded against the plates B which constitute the major facing of a mold and which are mounted between suitable supports C, assembled and held by stringers D. 70 The plates B are held in position by suitable locks E. Broadly speaking, elements corresponding to elements B, C, D and E are the essential parts commonly employed in building up molds for concrete construction work, 75 and it is to these and related connecting elements that the improvements constituting the present invention are particularly directed.

The plates B as herein disclosed are each 80 shown formed of a sheet metal blank having its ends bent up. Flanges angles and other parts on the outward side with suitable connecting means serve to reinforce the blank. The faces of these plates adjacent their mounting over the face flanges on the supports (hereinafter to be more fully described) are provided with recessed portions 85 b for clearing the flanges on the supports, so that a substantially flush facing for the 90 mold will be provided at said supports. These plates B it will be understood, may also be made from wood, and the specific construction thereof does not per se constitute the subject matter of the present invention. 95

The supports C, which may be employed either as studs or joists, are preferably made in channel shape and consist of a web portion c, a pair of lateral sides c' forming substantially right angles with the web and a pair of face-flanges c², bent outwardly from the lateral sides and forming therewith substantially right angles, all of which is best shown in Fig. 4. Between the lateral sides c' and preferably flush with the inner faces of the flanges c² is secured the wooden or equivalent facing F. This wooden or equivalent facing, which may be in the nature of a flat board, is permanently and securely held against movement with respect to the support in an improved manner by metal ties G, which constitute one of the important features of the present invention. The metal ties G, which are shown as open cornered, 110 rectangular boxes with one open face, may be formed in any known manner, and preferably by stamping from sheet metal blanks. These ties are positioned at suitable intervals within the supports with their closed faces toward the open face thereof, but inwardly positioned therefrom and suitably brazed, or arc-welded or otherwise fastened in place. By this means of fastening the metal ties in place all objectionable increases 115 in the thickness of the support flanges and other projections on the lateral faces of the support such as rivet heads are eliminated. Thus positioned the metal ties also form 120 with the lateral faces of the support a re-

ceiving channel for the wooden facing board F. To secure the board F in place within this channel, nails or other suitable instrumentalities f may be employed, which are shown driven through the face of the board just above or below the tie plates and bent back into holding engagement over the sides of the metal ties, as best shown in Figs. 2 and 4. The bending back of the nails may be accomplished by any blunt instrument passed through one of the several openings in the web portion of the support.

In order to readily clamp and unclamp the plates B in position over the extending flanges c², I have provided an improved quickly operative locking device H. As disclosed, this device consists of a slightly bent locking bar h, the insertable end h' of which is reduced and tapered and has upon it a lug or nose extending toward the mold space. Adjacent the insertable end h' the locking bar h also has a stop shoulder h² and at its other end a screw threaded opening through which passes a clamping screw h³ adapted to clamp against said plates B. The head of the clamping screw may be formed in any desired manner, and is herein shown as provided with transverse openings h⁴, located 90° apart, around said screw head, so that one or more openings will always be accessible and thus serve to accommodate a lever turning element which may be in the nature of a spanner wrench, and in the absence thereof, a common nail or other equivalent device will answer. For cooperating with said locking device, the lateral sides of the supports are provided with suitable large openings c³ and small openings c⁴ arranged in alternate relation with each other on each side of the support affixed distances apart, and in staggered relation with each other on the opposite sides of the support. That is to say, for each large opening c³ on one lateral side of the support there is arranged approximately opposite thereto on the other lateral side a small opening c⁴. Since it is desirable to avoid all projections on the lateral faces of the support so that the assembling of the plates B may be facilitated, the small openings c⁴ are preferably formed in depressed portions c⁵ of the sides c' so that the engaging noses h' of the locking members H will always lie below or flush with the outer surfaces of said lateral sides. In assembling the plates B between a pair of supports at any level, all that is necessary is to place the plate with its recessed edges b over the flanges c² and insert the locking bar h in the openings c³ so that the insertable ends h' emerge through the opposite openings c⁴, and then tighten the clamping screw h³ against the plate. In the course of this clamping action the insertable end h' of each locking member is caused to bear

against the edge of the hole c⁴ in a direction toward the mold space, and said edge thereby prevents movement of said locking member when the concrete is poured into the mold. It will be understood that the plates B are of uniform length horizontally, and are appreciably shorter than the distance between the lateral sides of adjacent supports between which they are assembled. Therefore, slight variations in the distances between the supports do not obstruct easy placing and removal of plates.

For the purpose of permitting the mounting of stringers at various points along the length of the support, the web portion of the support is provided with equidistantly spaced elongated openings c⁶ which are preferably rectangular in form and which are adapted to receive a special form of cleat and a T-bolt used in connection with the mounting and splicing of the stringers, and likewise employed in the splicing of the supports. These openings c⁶ and other openings c⁷ in the web portion of the support may also serve for the insertion and retention of the rod a, and also for the insertion of a blunt instrument to bend back the nail f over the sides of the tie-plates G. The top end of the support is preferably closed so as to prevent the ingress of cement or concrete into its interior during pouring operations and thus interfere with the proper working of the locks H.

It will be appreciated, that in the building of molds for concrete work it is advantageous to have the various elements of the molds standardized so that they may be repeatedly used without modification. Accordingly, the supports and stringers are made of standard lengths. In practice the stringers are known as one, two or three-stud stringers, and there is also provided what is known as an end stringer which is approximately half the length of a one-stud stringer and principally used where obstruction occurs such as an adjacent building, an inside wall corner, a pilaster or the sides of an excavation. In the drawings, the stringers are shown as formed of angle iron and are designated by the reference character D. For the purpose of splicing these stringers, I have provided an improved stringer splice K, which consists of a channelled member having a web portion k and side walls k', as shown in Figs. 7 and 8. In the web portion k of said splice, at a fixed distance apart, elongated rectangular openings k² are formed, said openings adapted to coincide with holes positioned in the stringers at a fixed distance from each nearest support, and through which holes the clamping bolts pass. The clamping bolts which are T-shaped, are employed with an improved bolt cleat, the bolt and

cleat being carried by the stringers in substantially D-shaped holes in which most of the bolts and cleats remain permanently assembled. A detailed description of the bolt cleat and D-shaped holes in the stringers will be given in connection with the description of the support splices wherein the same construction prevails.

In Figs. 5, 6 and 9 I have shown my improved support splice L, consisting of the angle member l which seats against the web and one face of the support, and the reinforcing channelled member l' which has its web spot welded to the angle member as shown at l², so that one of its sides and the second side of the angle member lie substantially in the same plane. The engaging face of the angle member l is formed with a series of D-shaped openings l³ all on the same line and so spaced as to be adapted to substantially coincide with the elongated openings c⁶ in the support. It also has other openings l⁴ which may also coincide with openings c⁶ and c⁷ in the support and thereby permit the passage therethrough of the tie rods or the like. A consideration of Figs. 5 and 9 will disclose that the reinforcing member l' is shorter than l, and where said first-mentioned member overlies the openings l³ in the angle member, it is formed with clearance openings l⁵. Although Fig. 5 shows the support splice free from all clamping bolts, it is to be understood that said member permanently carries the clamping bolts and bolt cleats. The bolt cleat as used in conjunction with this invention is shown in Figs. 11 and 12, and consists of a metal plate M having a tongue m stamped up therefrom and extending substantially at right angles to the plane of the plate. The width of the tongue m is such, as to permit its passage through the D-shaped openings in the support splice and stringers, and through the elongated openings c⁶ and l² in the support and stringer splice respectively. Its length should be sufficient to pass through at least three thicknesses of metal and still have a protruding portion sufficient to prevent the turning of the T-bolt as shown in Fig. 9. The tongue is the vital element of the cleat and it is necessary that said tongue be held substantially adjacent and parallel to the T-bolt and that it project from a stringer or a splice in the same direction as the head of the bolt. It is obvious that such a tongue may project in this manner even though constructed in a manner different from that herein shown, and it will be understood that I do not wish to be limited to the specific structure of the tongue herein disclosed. The cleat is merely an economical and practical means for holding the tongue in position on a stringer or a splice.

In mounting a stringer on a support, or

in splicing a support, the stringer or splicing member which carries the T-bolts and cleats is positioned in place, the T-bolt head turned so that it passes through the elongated opening in the support, and the bolt is then given a quarter turn to prevent its removal. The flat side of its head is then automatically engaged by the cleat tongue when the wing nut is turned to securely clamp the members in place. It is frequently desirable to employ an unthreaded sleeve in connection with the bolt, as shown in Fig. 10, said sleeve serving to prevent the threads on the bolt becoming damaged.

At the upper portion of Fig. 9, I have shown a special manner of attaching a stringer or other member to a support. Said manner of attachment may be conveniently employed near the corner of a wall or at any other point than at the standard centers where are provided the D-shaped openings in the stringers. According to said manner of attachment, the stringer is clamped against the face of the support through the medium of a Z-bar N, which seats against the stringer and is fastened to the support, by suitable T-bolts and bolt cleats entering the openings above and below the stringer. Obviously, a longer T-bolt will be used in connection with the fastening at the far end of the Z-bar from the support and it is preferable to use a spacing sleeve for the cleat used in connection therewith as shown at O.

From a consideration of the preceding description taken in conjunction with the drawings, it will be evident that I have provided practical means for accomplishing the various objects of the invention as set forth, and while I have herein disclosed the preferred embodiments of my invention, it will be understood that certain changes may be made therein without departing from the spirit of the invention.

What I claim is:—

1. A mold comprising a series of supports adjacent the mold space, plates between the supports and adjacent the mold space, each support having lateral sides of sheet metal spaced apart and perforated with holes at intervals longitudinally of the support, locks extending laterally from each support and holding the plates in position, and each lock comprising a member extending through two said holes, one in each of the lateral sides of the support and bearing toward the mold space in the hole in the lateral side of the support opposite the side on which said lock holds a plate in position.

2. A mold according to claim 1, wherein the hole in the lateral side of the support opposite to the side on which said lock holds the plate in position, is disposed in a depression in said lateral side.

3. A mold according to claim 1, wherein the inserted end of the lock member, has a lug or nose extending toward the mold space which functions to prevent lateral 5 movement of the lock with respect to the support.
4. A mold according to claim 1, wherein the lock member is provided with a shoulder adjacent its inserted end, to prevent 10 inserting said member too far into the support.
5. A mold comprising a series of supports adjacent the mold space, plates between the supports and adjacent the mold space, each 15 support comprising a channel of sheet metal with its lateral sides and web perforated with holes at intervals longitudinally of the support, locks extending through the holes in said lateral sides and holding the plates 20 in position, a metal tie connecting said lateral sides at a substantial distance from the web, said metal tie being secured by means wholly within the lateral sides and wood between the metal tie and the mold space.
- 25 6. A mold according to claim 5, wherein the wood is held in the support by an element passing through the wooden part and engaging said metal tie.
7. A mold comprising a series of supports 30 adjacent the mold space, plates between the supports and adjacent the mold space, each support comprising a channel of sheet metal with its lateral sides and web perforated with holes at intervals longitudinally of the 35 support, locks extending through the holes in said lateral sides and holding the plates in position, the support having within it a bearing surface substantially parallel to the molding face and at substantial distances 40 from both the web and the mold space.
8. A mold comprising a series of supports adjacent the mold space, stringers holding the supports at proper intervals apart, plates between the supports and adjacent the mold 45 space, slots in said supports, the long dimension of each slot extending longitudinally of the support and means for fastening a support to another member of the mold, said member having connected to it a 50 bolt and a bolt cleat, the bolt having a head narrower than said slots and longer than the width thereof so that the bolt head may enter and leave said slots without disconnecting the bolt from said member, said bolt head being engaged in one of said slots, the length of the head extending transversely of the length of the slot and prevented from rotating by a part of said cleat extending through the same slot as the bolt, said part of the cleat being adapted to enter and leave said slot 55 without disconnecting the cleat from said member.
11. A mold comprising a metal channeled member having openings in its web and lateral sides, the openings in the lateral sides being of two sizes, alternately arranged longitudinally of the member with respect to each side, and said openings of each size in each lateral side being arranged in staggered relation to the openings of the same 60 size in the opposite lateral side.
12. A mold comprising a metal channeled member having its lateral sides formed with laterally extending longitudinal bends adjacent the open channel, a metal tie connecting the lateral sides at a substantial distance from the web and wood between the metal tie and the mold space, said metal tie being secured to the channeled member by means wholly within the channel.
13. A mold comprising a metal channeled member having a metal tie connecting the lateral sides at a substantial distance from the web and wood between the metal tie and the mold space, said metal tie being secured to the channeled member by means wholly 65 within the lateral sides thereof.
14. A mold comprising a series of supports adjacent the mold space, stringers holding the supports at proper intervals apart, plates between the supports and adjacent the mold space, splices for connecting the stringers end to end, bolts for connecting the stringers to the splices, nuts on the bolts, bolt cleats for preventing the rotation of 70
- 75
- 80
- 85
- 90
- 95
- 100
- 105
- 110
- 115
- 120
- 125
- 130

- the bolts, and slots for receiving said bolts, the head of each said bolt being narrower than said slots and longer than the width thereof so that while the nut remains on the bolt, the bolt head may be inserted through any of said slots and thereafter turned transversely of the slot and engage the metal containing the slot when the nut is drawn tight for the purpose of holding a splice and stringer together, a part of each cleat extending through the same slot as a bolt and preventing rotation of the bolt head.
15. A mold according to claim 14 wherein the bolt cleat is carried by the bolt while, before and after the bolt head is engaged and disengaged through the slot in the metal.
16. A mold according to claim 14 wherein said cleat consists of a piece of sheet metal having a hole punched therein for encircling said bolt, the portion punched from said hole adhering to the sheet metal piece at one edge of the hole and extending transversely to the plane of said sheet metal piece from which it was punched, one end of said portion being the part extending through the slot and preventing said bolt from turning.
17. A mold comprising a series of supports adjacent the mold space, plates between the supports and adjacent the mold space, each support having slots, the long dimension of each slot extending longitudinally of the support, a member adapted to be fastened to the support by a bolt, a tongue for preventing rotation of said bolt, said tongue and bolt head projecting from the same side of said member, the bolt head being narrower than said slots and longer than the width thereof, the narrow dimension of the bolt head permitting it to enter and leave said slots without detaching the bolt from said member, said bolt head being engaged in one of said slots with the length of the head extending transversely of the length of the slot and prevented from rotating by said tongue extending through the same slot as the bolt, and the tongue being adapted to enter and leave said slot without detaching the tongue from said member.
18. A mold comprising a series of supports adjacent the mold space, stringer members holding the supports at proper intervals apart, plates between the supports and adjacent the mold space, splicing members for connecting the stringer members end to end, bolts for connecting the splicing members to the stringer members, nuts on the bolts, and tongues for preventing rotation of the bolts, one of the members having slots for receiving said bolts, the head of each said bolt being narrower than said slots and longer than the width thereof so that while the nut remains on the bolt, the bolt head may be inserted through any of said slots and thereafter be turned transversely of the slot and engage the metal laterally of the slot when the nut is drawn tight for the purpose of holding the members together, each tongue extending through the same slot as a bolt and preventing rotation of the bolt head.
19. A mold comprising a series of supports adjacent the mold space, and stringers for holding the supports at proper intervals apart, and bolts for uniting said parts at their intersections, said supports having elongated slots, the long dimension of each slot extending longitudinally of the support, the bolt heads being narrower than said slots and longer than the width thereof, the bolts and their nuts carried by the stringers, and means for engaging the bolt heads when extended transversely of the slots, to prevent their rotating, such means comprising a tongue extending through the same slot as the bolt and adapted to enter and leave said slot without detaching the tongue from the stringer.
20. A mold according to claim 18, wherein in both said bolt and said tongue are carried by the same member, while, before and after, the bolt head is being engaged and disengaged through the slot.
21. A mold according to claim 1, wherein a part of the edge of said hole in the lateral side of the support opposite to the side on which said lock holds the plate in position, constitutes a bearing seat for a part of said lock and is depressed at a substantial distance below the lateral surface of the support.
- In witness whereof, I have hereunto signed my name.

ROWLAND T. WALES.
